UNITED STATES PATENT OFFICE.

JOHN H. GIBSON, OF CRAFTON, PENNSYLVANIA, ASSIGNOR OF ONE-HALF
TO SAMUEL E. HARTZELL, OF CRAFTON, PENNSYLVANIA.

ICE-CUTTING MACHINE.

SPECIFICATION forming part of Letters Patent No. 758,963, dated May 3, 1904.

Application filed July 15, 1903; Serial No. 165,566. (No model.)

To all whom it may concern:

Be it known that I, JOHN H. GIBSON, a citizen of the United States of America, residing at Crafton, in the county of Allegheny and State of Pennsylvania, have invented certain new and useful Improvements in Ice-Cutting Machines, of which the following is a specification, reference being had therein to the accompanying drawings.

10. This invention relates to certain new and useful improvements in ice-cutting machines, and more particularly to that class of machines which are adapted to be placed on the river or pond from which the ice is to be cut, means being provided upon the machine whereby as the ice is cut motion is imparted to the machine whereby the same can readily travel over the ice.

Another object of my invention is to provide a machine which can be adjusted, whereby different thicknesses of ice may be cut, and means is provided upon the machine for cutting a plurality of pieces of ice and insuring an even width of cut throughout the length 25 of travel of the machine.

Briefly described, my invention consists in providing a rectangular framework mounted upon runners, and in said framework I provide a similar rectangular frame which is adjusted therein by means of a rack and pinion, and carried by said framework are spiked rollers which are adapted to engage the ice, also a plurality of toothed cutters or saws which are adapted to cut the ice, means being constructed within the rectangular framework to impart motion to each of the spiked rollers and the cutters simultaneously.

With the above and other objects in view the invention consists in the novel construction, combination, and arrangement of parts to be hereinafter more fully described, and specifically pointed out in the claims.

In describing the invention in detail reference is had to the accompanying drawings, forming a part of this specification, and wherein like numerals of reference indicate like parts throughout the several views, in which—

Figure 1 is a perspective view of the machine. Fig. 2 is a top plan view thereof. Fig. 3 is a detail view of one of the axles. Fig. 4 is a similar view of another of the axles. Fig. 5 is a detached detail perspective view of one of the racks employed for raising and lowering the machine. Fig. 6 is a side elevation of one of the casters employed on the front standards or uprights. Fig. 7 is an end view of one of the runners. Fig. 8 is a side elevation of the same, and Fig. 9 is a detail perspective view of one of the cutters or saws.

In the accompanying illustration of my invention I have shown the same as adapted to be operated by hand—that is, to operate both the cutters or saws and propel the machine forwardly through the medium of hand-power. However, it is the purpose of the present invention to construct a machine which may be operated by steam-engine, gasoline-engine, or other suitable power, and I therefore do not wish to limit myself in this application to the driving means shown, as in cases where a considerable quantity of ice is to be cut I will use a suitable engine for a motive power for propelling the machine and for operating the saws.

To put my invention into practice, I provide a rectangular frame embodying the side braces 2^a 2^b and end braces 3, which are secured to the standards 4 at the rear end of the machine by means of the angle-irons 5, and at the front end of the machine the braces are similarly secured to standards 4^a. The standards 4 carry the U-shaped guides 6, which receive the standards 7^a, that carry the racks 8 upon their sides, these racks being shaped to mesh with the pinions 9, journaled upon the shafts 10, said shafts being secured in the bearings 11 upon the inner side of the standards 4 4^a, and upon the outer end of the shafts 10 are secured the cranks 12. Secured on the lower ends of the standards 7 and 4^a are the runners, as illustrated in Fig. 8 of the drawings, said runners consisting of a plate 14, which is secured to the standards 7, and formed centrally of said plate and at right

angles thereto is the runner-blade 15. Upon the ends of the standards 7^a I provide the rollers 16, which are secured to the standards by any suitable means, these rollers being 5 provided for the purpose of facilitating the turning of the machine when the end of the cut is reached and it is desired to travel in the opposite direction.

Upon the side braces 2^b, which are similar 10 to braces 2, I mount the operating-shaft 19, this shaft being journaled in the bearings 20 upon the braces 2^b, and upon the outer ends of this shaft I provide the cranks 21, whereby the same may be rotated in any desired direction. Upon this shaft 19 I provide 15 a sprocket-wheel 22, around which passes chain 23, this chain engaging a sprocket-wheel 24, carried on the shaft 25, journaled in the bearings 26, carried by the side braces 20 20 2^a, which are similar to the side braces 2 and 2^b, respectively. On the shaft 25 I mount the sprocket-wheel 29, over which passes the sprocket-chain 30, which meshes over a sprocket-wheel 31, mounted upon a 25 shaft 32, journaled in boxings carried by the braces 33, these braces being secured to and supported by the standards 4 at the rear end of the machine. Upon the two ends of the shaft 32 and intermediate of its ends I mount 30 the cutters or saws 34, which are adapted to engage and cut the ice when the shaft 19 is rotated by the cranks 21, the motion of this shaft being imparted to these cutters or saws through the mechanism just described. Also 35 mounted upon shaft 19 are the sprocket-wheels 35 36 37, these wheels being of different size and splined on the shaft and movable lengthwise thereon, so that any one of these three wheels may be brought into alinement 40 with any one of the sprocket-wheels 35, 36, and 37, the object of which is to obtain a variance of the speed, as desired. Over the wheel 37 passes the sprocket-chain 37', said chain passing around the sprocket-wheel 38, 45 mounted upon the shaft 39, journaled in the bearings 40, which are carried by the side braces 2^a. On this shaft 39 are also mounted the sprocket-wheels 38^a 38^b and sprocket-wheels 41 42 43, which are also splined on the 50 shaft and movable lengthwise thereof, so that any one of them may be brought into alinement with the sprocket 44, the sprockets being of different size, so as to impart different rates of speed to the propelling-rollers 48. Over 55 the sprocket-wheel 43 passes the chain 43'. This chain also passes over a sprocket-wheel 44, mounted upon the shaft 45, which is journaled in the standards 4^a, and upon this shaft 45 I provide the toothed or spiked propelling- 60 rollers 48, which are adapted to engage the ice and force the machine in either one or the other direction. I provide the different-sized sprocket-wheels, whereby the chain may be

lengthened or shortened and a higher or lower speed imparted to the mechanism, as is desired. 65 To hold the frame in its adjusted position, I provide the pawls 49, carried by the standards of the frame, these pawls adapted to engage the pinions 9 and prevent the same from rotating when once placed in a desired position, whereby the frame may be held in a locked position in engagement with the racks 8 of the standards 4.

Upon the side braces 2 I provide a gage 50, which is held in the hinged bearings 51 upon 75 the side braces 2, the stem of this gage being provided with apertures 53, through which a pin may be passed into the side brace for securing the gage in the desired position. Upon the outer end of the stem of the gage 3 80 I provide the shoe 54, which is adapted to engage in the prior cut made by the saw in the ice. When the end of the cut is reached when traveling in one direction, the gage is removed and reversed, so the shoe will engage during 85 the return travel of the machine in the cut that was made by the outside saw. The bearings 51 are made hinged, whereby one of the same may be thrown back, and thus permit the elevating of the shoe end of the gage and the suspending of the same by the chain 52^c and staple or eye 52^b, whereby the shoe 54 is held elevated above the ice when desired.

It will readily be seen that the framework carrying the cutters or saws and the spiked propeller-rollers may be adjusted to any desired position, and that any desired speed may be imparted to the machine by the operator.

It is obvious that cutters or saws of any desired form may be employed and other slight changes may be made without departing from the general spirit of my invention.

Having fully described my invention, what I claim as new, and desire to secure by Letters Patent, is—

1. In an ice-cutting machine, the combination of a frame composed of vertical main standards and connecting side braces, supplementary standards slidably mounted on said main standards, rack-bars carried on said supplementary standards, a shaft journaled on said main standards, and pinions mounted on said shaft and engaging said rack-bars.

2. In an ice-cutting machine, a mechanism-supporting frame, standards operatively connected with said frame, racks carried by said standards, pinions carried by said frame and meshing with said racks, means for manually rotating said pinions, and means for preventing the rotation of said pinions.

3. In an ice-cutting machine, the combination of a mechanism-supporting frame composed of main front and rear standards and connecting-braces, the front standards having shoes on their lower ends, supplementary rear standards slidably mounted on the main rear

standards, shoes on the lower ends of said supplementary rear standards, supplementary front standards slidably mounted on the main front standards, wheels on said supplementary front standards and means for raising and lowering the supplementary standards at each end of the frame.

In testimony whereof I affix my signature in the presence of two witnesses.

JOHN H. GIBSON.
